UNITED STATES PATENT OFFICE.

ALEXANDER W. FINLAYSON, OF DETROIT, MICHIGAN.

RADIATOR CONSTRUCTION.

1,311,599.

Specification of Letters Patent. Patented July 29, 1919.

Application filed July 5, 1917. Serial No. 178,560.

To all whom it may concern:

Be it known that I, ALEXANDER W. FINLAYSON, a citizen of the United States of America, residing at Detroit, in the county 5 of Wayne and State of Michigan, have invented certain new and useful Improvements in Radiator Construction, of which the following is a specification, reference being had therein to the accompanying 10 drawings.

This invention relates to radiators and refers more particularly to a radiator construction such as adapted to the cooling systems of automobile engines, although the invention in its broader aspects is not necessarily limited to the particular use mentioned.

Among the objects of the invention are to provide a construction which can be built 20 up of a plurality of independently formed sections, preferably cast from aluminum or like material; to provide a construction in which access can be had to any of the sections independent of the other sections; to 25 so construct and arrange the parts that one or more of the units can be closed off from the cooling system so as to permit of varying the amount of radiating surface employed; to provide a construction in which 30 the water in passing through the system is compelled to baffle back and forth in such a manner as to greatly increase the efficiency of the radiator; to provide a construction which has greater rigidity than radiator 35 constructions now in use and which can be economically manufactured and assembled; and in general to provide an improved and simplified radiator construction of the character above referred to.

40 The invention also resides in such details of construction and arrangements and combinations of parts as will more fully herein-after appear.

In the drawings:

45 Figure 1 is a front elevational view of a radiator construction embodying my invention;

Fig. 2 is an enlarged elevational view partly in section of one of the center units 50 the plane of section cutting the rear portion of the unit, which portion is of reduced width;

Fig. 3 is a view similar to Fig. 1 of one of the end units;

55 Fig. 4 is a plan view of one of the center units;

Fig. 5 is a plan view of one of the end units;

Fig. 6 is a front elevational view partly 60 in section of the lower header;

Fig. 7 is a view of the upper header similar to Fig. 6;

Fig. 8 is a top plan view of the upper header;

Figs. 9 and 10 are detail views of one of 65 the tank plugs.

Describing in detail the particular construction shown in the drawings, and referring first to the general assembly, A designates an automobile radiator having the 70 usual open panel B, within the center portion of which there is exposed the cooling surface C. The cooling surface is built up of a plurality of independent center sections D, and end or side sections E, the particular construction of which sections is shown in detail in Figs. 2 and 3. At their 75 upper ends these sections are connected into an upper header F and at their lower ends into a lower header or tank G. The latter 80 is provided with the usual pipe connection H, while the upper header has in addition to the pipe connection I, the usual filler opening I'.

In the operation of the radiator the cooling fluid is inserted through the filler opening and flows from one header to the other through the various radiator sections and then from the pipe connection to the jacket of the engine or other member to be cooled. 85

Describing now in detail the construction 90 of the units and their assembly with relation to the headers, it will be noticed in Fig. 2 that the center units are formed with a main vertical portion J having laterally extending side flanges J' and J'', these flanges being spaced apart a sufficient distance to receive the projecting flanges of the next adjacent section, as shown in Fig. 2, and to 95 also leave the necessary air spaces through which the air can flow over the cooling surfaces formed by the walls of the flanged portions. In order to produce a more efficient cooling action, each of the flanged portions is provided with a sheet-metal baffle plate 100 K said flanged portions being cast around the baffle plates. In the formation of the unit, these baffle plates are mounted upon a hollow rod L' which also forms a spacer rod 105 to hold the plates in proper spaced relation when the section is cast. Near their outer ends the baffle plates are provided with pas-

sages L^2 , L^3 and L^4 , the arrangement of parts being such that as the water passes from the main upright part J , it is compelled by the baffle plate to flow transversely throughout the length of the flange, first on one side of the baffle plate and then returning on the other side in order to reach the next part of the main vertical portion J .
 The construction of the end units E and E' is similar to that of the center units except that one of the flanges J' and J^2 is omitted and the end of the baffle plate similarly received in a short recess J^4 . At their upper and lower ends the main parts J of the sections are enlarged and internally threaded at M and M' respectively to receive the cooling section connecting nipples N . These nipples have an enlarged head N' which is drawn tightly against the seats N^2 in the headers. Thus when the main upright portion J of the section is brought into registration with the seats N^2 in the upper and lower headers and the connecting nipples screwed into the threaded portions M and M' , the unit will be locked tightly to the headers and will have internal communication to the headers through the openings N^3 in the connecting nipples. To facilitate the assembly and also the repair or replacement of any section the upper header is provided with a series of enlarged threaded openings O in registration with its seats N^2 , these openings being of sufficient size to permit the insertion of the connecting nipple through the opening, while the lower header G is provided with a similar set of threaded openings O' through which the connecting nipples for fastening the lower ends of the cooling sections can be inserted.
 The threaded openings O and O' are closed by suitable tank plugs O^3 , these plugs preferably having a wrench-receiving portion O^4 by which they can be screwed into or out of the threaded openings O and O' . Not only does this arrangement of the connecting nipple facilitate the assembly and independent repair or renewal of the units, but it also permits of the closing off of any section or sections from the cooling system by simply substituting for the usual connecting nipple N a nipple N^5 having a closed head, that is, one in which the passage N^3 is omitted. It is therefore possible to regulate the amount of cooling surface by simply substituting one type of nipple for the other and also in case of injury to one of the sections, that particular section can be cut out of the system by putting in the closed end connecting nipple. The particular shape of the units is shown in the top plan views, Figs. 4 and 5, wherein it is seen that the flanges J' and J^2 are of reduced

width in their rear portions so as to permit the front portions of said flanges to overlap the tubular portions J of the adjoining units. In the top and bottom flanges of each unit there is a somewhat greater reduction in the width of the rear portion in view of the enlargement of the end portions of the members J .
 70

From the above description it will be apparent that a radiator constructed in accordance with my invention can be cast from aluminum or other desired material and that even in the assembled arrangement the sections remain independent, that is, they can be independently detached for repair or renewal and that any desired section or sections can be easily cut out from the cooling system. Various changes, however, in the 80 details of construction and arrangements and combinations of parts can be made within the scope of my invention.

What I claim as my invention is:

1. In a radiator, a unit comprising an 85 integral cast metallic member having a central longitudinally extending portion formed with a series of enlargements therein and sheet-metal baffle plates respectively located within said enlargements.
 90

2. In a radiator, a unit comprising an integral central longitudinally extending portion having a series of enlargements therein, baffle plates located respectively within said enlargements and a member arranged within the central portion of said unit and connecting said baffles in a fixed relation.
 95

3. A radiator, comprising top and bottom headers, a plurality of units connecting said headers having open ends registering with openings in said headers, nipples extending through said openings and detachably engaging the ends of said units, the lower face of the lower header and the top face of the upper header being apertured in registration with said units giving access through the headers to said nipples whereby said units are independently detachable.
 100

4. A radiator, comprising top and bottom headers, a plurality of units connecting said headers and having open threaded ends registering with openings in said headers, threaded nipples extending through said openings and engaging the threaded ends 115 of said units, the lower face of the lower header and the top face of the upper header being apertured in registration with said units to give access through said headers to said nipples to permit of separately detach- 120
 ing said units from said headers.

In testimony whereof I affix my signature.

ALEXANDER W. FINLAYSON.
